Primary Examiner — Cathron Brooks*Assistant Examiner* — Teddy Falloway(74) Attorney, Agent, or Firm — Birch, Stewart, Kolasch & Birch, LLP(57) CLAIM

The ornamental design for a tablet PC, as shown and described.

DESCRIPTION

FIG. 1 is a perspective view of a tablet PC showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines shown in the figures that are immediately adjacent to the shaded areas and define regions that are consistently unshaded, represent the bounds of the claim, while all other broken lines, including those within the broken line boundaries, are directed to environment; the broken lines form no part of the claimed design.
